CINDER NOTCH STOPPER

August F. Giese, Jr., Gary, Ind.

Application November 24, 1942, Serial No. 466,771

5 Claims. (Cl. 266—42)

This invention relates to a cinder notch stopper for blast furnaces, and particularly to an improved apparatus for mounting and operating the same.

Heretofore, various types of devices and apparatus have been suggested and used for plugging or closing the cinder notch or cinder tapping hole of blast furnaces. Such devices are generally called cinder notch stoppers or botter rods. While such devices heretofore proposed were effective generally for the purposes contemplated, they were objectionable due to mechanical difficulties in the construction and operation thereof. Oftentimes the stopper on the end of the stopping or botting rod becomes stuck in the cinder notch during the use thereof and in existing devices sufficient force could not be applied by the operating mechanism to force effectively the stopper bar from its position in the monkey of the cinder notch. At times it was necessary to subject the stopper or botting rod to blows by a hammer or sledge in order to release it and to start the movement of the stopper bar from its position in the monkey of the cinder notch. Such procedure was not only tedious and laborious but was extremely dangerous to the operator.

Furthermore, such cinder notch stopping mechanism as heretofore suggested was complicated and consisted of an excessive number of movable parts which, of course, made such devices expensive as well as difficult to use. Such devices were also cumbersome and occupied a relatively large amount of space in the vicinity of the cinder notch of the blast furnace. Also, such devices as proposed were usually relatively flimsy in their construction and required frequent repairing and replacement of parts.

Accordingly, it is one of the objects of the present invention to provide an improved apparatus for supporting and operating cinder notch stoppers which is simple and inexpensive in its construction and use at the same time, apparatus which is efficient, effective and safe in its use.

It is another object of the invention to provide an improved apparatus for supporting and operating cinder notch stoppers which is compact and consists of a minimum number of parts, and at the same time apparatus which is strong and rugged in its construction, thereby reducing maintenance and replacement costs to a minimum.

It is a further object of this invention to provide an improved apparatus for supporting and operating cinder notch stoppers with which there is incorporated means whereby a hammering ac-

tion can be obtained axially upon the stopper bar so as to remove effectively the same from its position in the cinder notch.

It is still another object of the present invention to provide improved apparatus for supporting and operating cinder notch stoppers which is positive in its movement and which can be easily and quickly moved to its operating position opposite the cinder notch and to a retracted position above and away from the cinder notch, thereby permitting the operator to close quickly the cinder notch of the furnace.

Various other objects and advantages of this invention will become more apparent during the course of the following specification and will be particularly pointed out in the appended claims.

In the accompanying drawings there is shown for the purpose of illustration, an embodiment which my invention may assume in practice.

20 In the drawings:

Figure 1 is a side elevational view of the improved cinder notch stopper of my invention showing the position in which it is mounted in relation to the blast furnace;

25 Figure 2 is a front elevational view thereof;

Figure 3 is a plan view of the same;

Figure 4 is a longitudinal sectional view through the lower part of my improved cinder notch stopper; and

30 Figure 5 is a sectional view taken on line V—V of Figure 4.

Referring more particularly to the drawings, in Figures 1 and 4 a blast furnace wall 2 is shown having a cinder notch 3 therein in which there is disposed a large frustro-conical-shaped cooler 4 and a smaller cooler 5 inserted in the end of the large cooler 4 with still a smaller cooler or cinder notch monkey 6 having an opening 7 therethrough which is adapted to be closed by a stopper or plug in a well-known manner.

According to the present invention as shown in Figures 1, 2 and 3, there is arranged above the cinder notch 3 on the outer side of the blast furnace wall between the same and the furnace bustle pipe B, a vertically extending bracket member 8 having a pair of oppositely disposed vertically extending guideway grooves 9 carried thereby. The upper end of the bracket 8 is attached preferably to a structural member 10 by means of bolts 12 and the structural member in turn is supported by straps or bands 13 which extend preferably around the columns of the furnace with the ends of the structural member 10 being attached to the straps 13 by means of bolts

55 14. The lower end of the bracket member 8 is

attached preferably to the tuyère jacket of the furnace by means of bracket members 15 and bolts 16.

There is carried by the bracket 8, preferably an L-shaped head 17 which is mounted for slidable movement in a vertical plane. There is carried by the head to each side thereof a flange portion 9a which fits into and cooperates with the grooves 9 in the bracket 8 so as to guide the head in its vertical movement. There is also mounted on the bracket 8 and secured thereto, preferably by means of bolts 18, a vertically disposed pneumatic cylinder 19 with the lower end of the piston rod 20 thereof attached to the movable head 17 as at 21. The pneumatic cylinder 19 is provided for moving the head 17 reciprocably in substantially a vertical plane relative to the bracket 8.

On the lower end of the head 17, there is mounted preferably a bracket member 22 which is secured to the head preferably by means of bolts 23. There is carried by the bracket 22, a member 24 which is mounted for slidable movement in substantially a horizontal plane. There is carried by the bracket 22, to either side thereof, flange portions or tracks 25 which cooperate with a pair of oppositely disposed guides 26 carried by the slidable member 24. There is also mounted on the bracket member 22, a horizontally disposed pneumatic cylinder 27 with the outer free end of the piston rod 28 thereof extending through a hole 29 arranged through a yoke-like portion 30 which is arranged on the end of the slidable member 24. The pneumatic cylinder 27 is provided for moving the slidable member 24 reciprocably in substantially a horizontal plane relative to the bracket 22. On the extreme outer end of the piston rod 28 of the pneumatic cylinder 27 beyond the hole 29 through the yoke-like portion 30 of the slidable member 24, there is arranged a pair of lock nuts 31 which are adapted to cooperate when the piston rod 28 is in one position with the outer side of the yoke-like portion 30 of the slidable member 24 to move the slidable member 24 inwardly. There is also mounted on the piston rod 28, an abutting member in the form of a collar 32 which is positioned on the piston rod at a point on the inner side of the hole 29 and the yoke-like portion 30 and at a spaced distance from the inner side thereof for a purpose hereinafter to be described. The abutting member or collar 32 is adapted to cooperate when the piston rod 28 is in one position with the inner side of the yoke-like portion 30 to move the slidable member 24 outwardly.

On the lower side of the slidable member 24, there is arranged preferably a pair of spaced apart, downwardly extending, arm-like portions 33 with each having a journal-like portion 34 arranged on the extreme lower end thereof. There is disposed in the journal-like portions 34 of the arm-like members 33, a horizontally disposed stopper bar or botting rod 35 with the outer free end thereof extending beyond the inner end of the slidable member 24. There is carried by the stopper bar intermediate the length thereof, a pair of spaced apart thrust members 36 between which journal-like portions 34 are disposed. The journal-like portions 34 are arranged preferably in two halves having bolts 37 arranged therethrough, whereby the stopper rod 35 may be removed from position therein. On the extreme outer free end of the stopper rod 35 there is mounted a hollow stopper 38 which is adapted to cooperate with the opening 7 in the monkey 6 so as to close the cinder notch open-

ing of the furnace in a manner well known to those skilled in the art.

As shown more clearly in Figures 4 and 5 of the drawings, the stopper or botting rod 35 is preferably hollow and there is disposed therewithin preferably a relatively small pipe 39 for conveying a cooling fluid such as water into and through the stopper rod. There is arranged on the inner end of the stopper rod 35, a suitable connection 40 through which the cooling fluid or water is introduced into the pipe 39 within the stopper rod 35. The water enters the pipe 39 through the connection 40 from any suitable source of supply (not shown) and flows through the pipe 39 the full length of the stopper rod and into hollow stopper 38. The water then flows back through the stopper rod between the outer wall of the small pipe 39 and the inner wall of the stopper rod 35 and is discharged from the stopper rod through a suitable outlet 41 to any suitable discharge means (not shown).

As shown in Figures 1 and 2 of the drawings, there is arranged preferably on the side of the head 17, a bracket 42 on which there is mounted an adjustable stop screw 43 which is adapted to cooperate preferably with a projecting portion 44 arranged on the lower end of the vertically disposed bracket member 8 so as to limit the downward movement of the head 17. There is also arranged preferably to one side of the bracket member 8, a pawl-like member 45 which is pivotally attached intermediate the length thereof to the side of the bracket member as at 46. Through the side wall of the bracket member 8, to one side thereof, opposite the guideway groove 9 therein, there is arranged an opening 47 in which the inner end of the pawl-like member is disposed and is adapted to cooperate with a notch 48 arranged in the side of one of the track-ways or flanges 9a of the head 17. It is the purpose of the pawl 45 to cooperate with and to be disposed in the notch 48 of the head 17 when the head is positioned in its upper or retracted position so as to lock the head in such position, whereby unintentional movement of the same is prevented.

The improved cinder notch stopper of my invention functions in the following manner. After the cinder has been withdrawn from the top of the molten metal in the blast furnace through the cinder notch 3, it is then desired to plug the cinder notch so as to prevent any further discharge through the same. The pawl 45 is first moved about its pivotal connection 46 by means of the downwardly extending handle arranged therewith so that the inner end of the pawl is moved out of the notch 48 in the head 17 so as to permit movement of the head. The head 17, together with the sliding member 24 and stopper rod 35 carried thereby, is then moved and lowered by means of the pneumatic cylinder 19 to a position as shown in the full lines of Figure 1, so that the stopper rod is opposite the opening 7 in the monkey 6 of the cinder notch. The downward movement of the head 17 so as to position the stopper bar 35 properly relative to the cinder notch, is limited by means of the adjustable screw 43 which abuts against the projecting portion 44 of the bracket 8. It will be understood that if the stopper rod is not positioned properly or centered relative to the cinder notch when the head has reached this lowermost position, the nuts carried by the adjusting screw 42 may be loosened and the adjusting screw moved so that the stopper rod 35 is in the proper position and

centered when the screw 43 abuts the stop or projecting portion 44.

After the head 17 has been moved to its lower position the slideable member 24, together with the stopper rod 35 and stopper 38 carried thereby, is moved horizontally on to the right as shown in Figure 1 of the drawings, by means of the pneumatic cylinder 27 until the stopper 38 is positioned properly in the opening 7 of the monkey 6. It will be seen that when the pneumatic cylinder 27 is actuated to move the slideable member 24, the nuts 31 on the outer end of the piston rod 28 thereof abut against the outer side of the yoke-like portion 30 of the slideable member 24 to move the same together with the stopper rod carried thereby.

When it is desired to remove the stopper from its position in the cinder notch and monkey the pneumatic cylinder is actuated in the opposite direction so that the stopper rod will move to the left as shown in Figure 1 of the drawings and away from the cinder notch. In such a movement it will be seen that the slideable member 24 together with the stopper rod 35 will not move until the collar 32 carried by the piston rod 28 moves to a point next to the inside of the yoke-like portion 30 of the slideable member and abuts thereagainst. Oftentimes the stopper 38 sticks in the cinder notch and it is difficult to move the same therefrom by providing merely a pulling action. In other words, it is necessary to transmit blows or a great amount of force to the stopper rod in order to remove the stopper from its position in the cinder notch. In the present instance such blows are provided by working the piston rod 28 back and forth reciprocably relative to the slideable member 24. That is, a hammering action is provided by the collar 32 carried by the piston rod 28 when it strikes the inner side of the yoke-like portion 30 of the slideable member 24 and thereby transmits a hammering action to the stopper rod 35 together with the stopper 38. The piston rod, together with the collar 32, may be made to reciprocate back and forth as often as is necessary to transmit such hammering action to the stopper rod and stopper until the stopper has become loosened and may be removed from its position in the cinder notch by means of a straight pulling action. The pneumatic cylinder is then made to withdraw the slideable member 24 together with the stopper rod carried thereby to their retracted position so that the stopper rod and stopper are out of the cinder notch. The head 17 is then moved upwardly to position as shown in the broken lines of Figure 1, by means of a pneumatic cylinder 19 to its upper or retracted position away from the cinder notch. When the head 17 has reached its upper position, the inner end pawl-like member 45 will automatically drop into the notch 48 in the side of the head 17 so as to lock securely the head in its upper position.

As the result of my invention it will be seen that there is provided a cinder notch stopper arrangement which is extremely simple in its construction and use and one that may be easily and conveniently manipulated by a single operator. It will also be seen that in the cinder notch stopper arrangement of my invention, the stopper will be disposed accurately opposite the cinder notch and disposed positively therein without incurring any undue danger to the operator or other workers in the vicinity of the furnace.

It will be seen that the improved cinder notch stopper apparatus of my invention is mounted

between the furnace bustle pipe B and the furnace in the limited space therebetween. The head of the apparatus is so designed that it will lie compactly in the space between the bustle pipe and the furnace and yet is not attached to the bustle pipe or mounted so close thereto as to be affected by the heat passing therethrough. In other words, the expansion and contraction of the bustle pipe will not affect the operation of my improved cinder notch stopper which is a decided advantage. In devices where the stopper arrangement is attached to the bustle pipe, the expansion and contraction thereof throws the cinder notch stopper out of center alignment with the monkey of the blast furnace. Accordingly, it will be seen that such a disadvantage is eliminated in the cinder notch stopper of the present construction.

While I have shown and described one specific embodiment of my invention, it will be understood that this embodiment is merely for the purpose of illustration and description and that various other forms may be devised within the scope of my invention, as defined in the appended claims.

I claim:

1. Apparatus of the class described comprising a head, means for moving said head in substantially a vertical plane, a horizontally disposed stopper bar, a stopper arranged on the outer end of said stopper bar, means carried by said head for supporting said stopper bar, said last-mentioned means being arranged for slideable movement relative to said head in substantially a horizontal plane, and a pneumatic cylinder carried by said head for moving said last-mentioned means together with the stopper bar carried thereby, the piston rod of said pneumatic cylinder connected to said last-mentioned means so as to permit a limited movement thereof relative to said head whereby a hammering action can be obtained upon said last-mentioned means together with said stopper bar.

2. Apparatus of the class described comprising a head, means for moving said head in substantially a vertical plane, a horizontally disposed stopper bar, a stopper arranged on the outer end of said stopper bar, a member carried by said head for supporting said stopper bar, said member being arranged for slideable movement relative to said head in substantially a horizontal plane, a pneumatic cylinder carried by said head for moving said slideable member together with the stopper bar carried thereby, said slideable member having an opening arranged in one end thereof through which the piston rod of the pneumatic cylinder extends, a nut arranged on the outer end of the piston rod beyond the opening in said slideable member, an abutting member mounted on said piston rod at a point on the inner side of said opening and at a spaced distance therefrom and from said nut so as to provide a limited lost motion between said piston rod and said slideable member whereby a hammering action can be obtained upon said slideable member together with the stopper rod carried thereby upon the actuation of said pneumatic cylinder.

3. Apparatus of the class described as defined in claim 2 including an adjustable means for limiting the downward movement of the head.

4. Apparatus of the class described as defined in claim 2 including means for locking the head in its upper or retracted position.

5. Apparatus of the class described comprising a movable head, a pneumatic cylinder for moving said head in substantially a vertical plane, a horizontally disposed stopper bar, a stopper arranged on the outer end of said stopper bar, a member mounted in the lower end of said head for supporting said stopper bar, said member being arranged for slidable movement relative to said head in substantially a horizontal plane, a pneumatic cylinder carried by said head for moving said slidable member together with the stopper bar carried thereby, said slidable member having an opening arranged in one end thereof through which the piston rod of said second-men-
- tioned pneumatic cylinder extends, a nut arranged on the outer end of said piston rod beyond the opening in said slidable member, a collar securely mounted on said piston rod at a point on the inner side of said opening and at a spaced distance therefrom and from said nut so as to provide a limited lost motion between said piston rod and said slidable member whereby a hammering action can be obtained upon said slidable member together with said stopper bar carried thereby upon the actuation of said pneumatic cylinder.

AUGUST F. GIESE, JR.
